UNITED STATES PATENT OFFICE.

GEORGE L. DANFORTH, JR., OF CHICAGO, ILLINOIS, ASSIGNOR TO OPEN HEARTH COMBUSTION COMPANY, OF CHICAGO, ILLINOIS, A CORPORATION OF DELAWARE.

OPEN-HEARTH FURNACE.

Application filed July 5, 1924. Serial No. 724,362.

To all whom it may concern:

Be it known that I, GEORGE L. DANFORTH, Jr., a citizen of the United States, residing at Chicago, in the county of Cook and State 5 of Illinois, have invented certain new and useful Improvements in Open-Hearth Furnaces, of which the following is a specification.

This invention relates to a new and improved open hearth furnace and more particularly to an open hearth furnace of the damper type.

Open hearth furnaces are double ended and the products of combustion alternately 15 pass out opposite ends. Consequently in fixed end furnaces the port design has to be a compromise between that most satisfactory for introducing the gas and air and that most satisfactory for carrying away the 20 products of combustion. In order to provide a more efficient port design furnaces have been made with auxiliary ports adapted to carry off the products of combustion, but provided with dampers to close them 25 off on the incoming end of the furnace. In this way a small incoming port area may be provided so that adequate direction and velocity may be given the flame while adequate outgoing port area may be provided 30 for carrying out the products of combustion without the resistance due to small passages.

In certain types of furnaces having auxiliary ports controlled by dampers, the gas uptakes have been comparatively small and 35 the gas has been introduced at comparatively high velocity. Such a construction gives a maximum amount of mixture with the air in the port with consequent large amount of combustion in the port. This has 40 resulted in a corresponding shortage of combustion in the chamber and also has required an excessive amount of water cooling. Another detrimental effect of the small gas uptake lies in the fact that but a small portion 45 of the products of combustion are carried through the port and consequently the heating effect upon the gas regenerator checker-work is very materially less than that upon the air regenerator checkerwork.

50 It is an object of the present invention to provide a new and improved furnace construction in which auxiliary outgoing ports are provided and in which the gas is introduced into the incoming port through an

uptake of comparatively large area whereby 55 the gas may be introduced at relatively low velocity.

It is a further object to provide construction of this character in which the dampers controlling the auxiliary ports are located 60 well back from the furnace and preferably approximately upon the line of the rear end of the opening of the gas uptake into the incoming port.

It is a further object to provide a furnace 65 of this type in which the air uptakes discharge behind the lateral dampers and behind the discharge of the gas uptake into the incoming port.

Other and further objects will appear as 70 the description proceeds.

I have illustrated a preferred embodiment of my invention in the accompanying drawings, in which—

Figure 1 is a vertical section of the fur- 75 nace end;

Figure 2 is a section taken on line 2—2 of Figure 1; and

Figure 3 is a section taken on line 3—3 of Figure 2. 80

The incoming port 11 is located opposite the center of the furnace hearth 10. This port is defined by the vertically extending longitudinal walls 12 which are located upon either side of the entrance of the gas 85 uptake 13 into the bottom of the port. The lateral outgoing ports 14 are defined between walls 12 and the side walls 15 of the furnace. The dampers 16 connect the rear ends of the walls 12 with the side walls of the furnace 90 and close off the rear ends of the lateral ports 14.

The air uptakes 17 discharge into the end of the furnace immediately in the rear of the dampers 16. These uptakes 17 are located laterally of the gas uptake 13 and in the rear of it. It will be noted that the dampers 16 are approximately in the plane of the rear end of the opening of the gas uptake 13 into the incoming port. 100

The dampers 16 are provided with the water cooled frame 18 and rest against the water cooled guides 19. The dampers are operated vertically by means of cable 20 passing over pulley 21 and may be drawn 105 up into the housing 22 entirely out of the furnace.

The walls 12 are provided with suitable

water cooling means 23. The heel 24 of the gas uptake opening is also provided with water cooled means 25.

It will be observed that the opening of the gas uptake into the port is comparatively large and that the gas may be introduced at relatively low velocity. The air coming up through the uptakes 17 is caused to move laterally by the dampers 16 which are immediately in the front of the uptakes and the air is directed out over the heel 24 and intersects the stream of gas from the gas uptake. This construction affords adequate mixture between the air and the gas so that not sufficient flame is generated in the port to burn away the port and yet so that the maximum heating effect is on the incoming side of the bath in the furnace chamber. The flame does not extend far enough to burn away the ports on the outgoing end.

On the outgoing ends the dampers 16 are raised and the products of combustion pass out both through the lateral ports and the incoming port. It will be apparent from Figure 1 that the greater amount of the products of combustion passing through port 11 will go down through the gas uptake 13 and will serve to heat the gas regenerator.

One preferred form of my invention has been shown by way of illustration only and I contemplate such changes and modifications to meet varying conditions, as may come within the spirit and scope of the appended claims.

I claim:

1. In an open hearth furnace, a centrally located gas uptake opening into the furnace end at a point in advance of the end wall, vertically extending longitudinal walls located adjacent the sides of the gas uptake opening, dampers adapted to close the side ports formed between the longitudinal walls and the furnace side walls, and air uptakes opening into the furnace in the rear of the dampers.

2. In an open hearth furnace, a centrally located gas uptake opening into the furnace end at a point in advance of the end wall, vertically extending longitudinal walls lo-

cated adjacent the side of the gas uptake opening, dampers adapted to close the side ports formed between the longitudinal walls and the furnace side walls, the dampers being located in approximately the plane of the rear end of the longitudinal walls, and air uptakes opening into the furnace in the rear of the dampers.

3. In an open hearth furnace, a centrally located gas uptake opening into the furnace end at a point in advance of the end wall, vertically extending longitudinal walls located adjacent the side of the gas uptake opening, dampers adapted to close the side ports formed between the longitudinal walls and the furnace side walls, the dampers being located approximately the plane of the rear end of the longitudinal walls and of the rear edge of the gas uptake opening, and air uptakes opening into the furnace in the rear of the dampers.

4. In an open hearth furnace, a centrally located gas uptake opening into the furnace end at a point in advance of the end wall, vertically extending longitudinal walls located adjacent the side of the gas uptake opening, and extending from approximately the rear edge of the opening to a point in advance of the front edge thereof, air uptakes located rearwardly and laterally of the gas uptakes, and dampers adapted to close the openings between the side walls and longitudinal walls.

5. In an open hearth furnace, a centrally located gas uptake opening into the furnace end at a point in advance of the end wall, vertically extending longitudinal walls located adjacent the side of the gas uptake opening, and extending from approximately the rear edge of the opening to a point in advance of the front edge thereof, air uptakes located rearwardly and laterally of the gas uptakes, and dampers adapted to close the openings between the side walls and longitudinal walls, the dampers extending in approximately the plane of the rear edge of the gas uptake opening.

Signed at Chicago, Illinois, this 25th day of June, 1924.

GEORGE L. DANFORTH, JR.
